UNITED STATES PATENT OFFICE.

ELMER H. HAVENS, OF ALBANY, NEW YORK, ASSIGNOR OF ONE-HALF TO CHARLES W. HALLENBECK, OF ALBANY, NEW YORK.

COMPOSITION TIE AND RAIL-FASTENER.

1,241,970.

Specification of Letters Patent.

Patented Oct. 2, 1917.

Application filed March 20, 1917. Serial No. 156,058.

To all whom it may concern:

Be it known that I, ELMER H. HAVENS, a citizen of the United States, residing at Albany, in the county of Albany and State 5 of New York, have invented new and useful Improvements in Composition Ties and Rail-Fasteners, of which the following is a specification.

This invention relates to railroad ties and 10 particularly to ties of the reinforced concrete type.

The object of the present invention is to provide a tie made of concrete or analogous material which will be effectually reinforced 15 so as to prevent breaking, the reinforcing means also providing means for anchor bolts by means of which the rail may be secured to the tie.

A further object is to provide a tie of the 20 above description in which the reinforcing means will be prevented from creeping longitudinally of the tie due to the alternate placing upon and removal of weight from the tie.

25 A still further object of the invention is to provide a tie which is of simple and cheap construction and one in which the rail may be quickly and securely placed in position thereon.

30 With the above and other objects in view the invention consists of the following novel combination and arrangement of parts to be hereinafter more fully described and illustrated in the accompanying drawings, 35 in which;

Figure 1 is a plan view of a railroad tie embodying the present invention and having a pair of rails in position thereon;

Fig. 2 is a longitudinal sectional view 40 through the tie and rail, showing the rail clamping bolts and reinforcing tie rods in elevation;

Fig. 3 is a cross sectional view on the line 3-3 of Fig. 2;

45 Fig. 4 is a perspective view of the tie with the rods and V-bolts shown therein by dotted lines; and

Fig. 5 is a perspective view of one of the V-bolts.

50 Referring to the drawings in detail the improved tie consists of a longitudinal member 10 which is composed of concrete or similar material, it being preferably formed of a mixture of concrete and cinders. Em-

bedded in the tie near each of its ends are 55 a pair of V-shaped clamp securing bolts 11, the said bolts being provided with substantially vertically extended end portions 12 which are adapted to project through the upper face of the tie and to receive thereon 60 rail clamping plates 13, by means of which the rails R are secured to the tie, nuts 14 being engaged with the threaded ends 12 of the said V-bolts as shown. The rail clamping plates 13 are cut away along 65 their inner and under edge as shown at 15 in order to accommodate the base flanges of the rail as shown.

In order to reinforce the tie and to provide means for anchoring the bolts 11 in 70 position therein, the said tie is provided with a reinforcing and anchoring bar 16, preferably formed of twisted steel. The ends of this bar are formed with laterally bent portions 17 for the purpose of securely 75 holding the bar in position and preventing any tendency to creep due to the alternate placing upon and removal of weight on the tie. To further reinforce the tie there are provided longitudinal reinforcing bars 18 80 which pass through and engage the inner sides of the V-shaped bolt 11 and act as spreaders for the bolt to hold the ends 12 in proper spaced relation.

From the foregoing description when 85 taken in connection with the accompanying drawings it will be seen that the invention provides a reliable reinforced concrete tie, which is of simple and economical construction, at the same time providing means for 90 quickly and effectually securing a rail thereto. This tie and its rail securing means are especially adaptable to switches, and for this purpose the rail clamping plates may have duplicate undercut portions 15 on each 95 side of the bolt 11 for the purpose of securing the adjacent switch or siding rails.

Having described the invention what I claim, is.

1. A tie of the class described having 100 longitudinal reinforcing rods embedded therein, V-bolts engageable with said rods for securing rail clamps to the tie and means whereby said rods are caused to act as spreaders for said bolts.

2. A tie of the class described having V-shaped clamp securing bolts embedded therein, longitudinal reinforcing and spreading

rods passing through and engaging said bolts and a longitudinal reinforcing and anchoring rod also passing through and engaging said bolts.

5 3. A tie of the class described having clamp securing bolts embedded therein, longitudinal reinforcing and spreading rods

passing through and engaging said bolts, a longitudinal reinforcing and anchoring rod also passing through and engaging said 10 bolts and laterally bent ends on all of said rods.

In testimony whereof I affix my signature.

ELMER H. HAVENS.
